UNITED STATES PATENT OFFICE.

CLAYTON EARL OSBURN, OF DAVENPORT, IOWA, ASSIGNOR OF ONE-HALF TO
WALLACE P. PETERSON, OF DAVENPORT, IOWA.

PRICE-CARD HOLDER.

1,403,100.

Specification of Letters Patent. Patented Jan. 10, 1922.

Application filed July 26, 1921. Serial No. 427,760.

To all whom it may concern:

Be it known that I, CLAYTON E. OSBURN, a citizen of the United States, and a resident of Davenport, in the county of Scott and the State of Iowa, have invented certain new and useful Improvements in Price-Card Holders, of which the following is a specification.

This invention relates to a price card holder.

The object of the invention is to provide a card holder of the above character which may be secured to cans, boxes, or the like, in which different commodities are retailed from grocery stores or the like for displaying a card having written thereon the price at which the commodity is to be sold.

It is also an object of the invention that the card be simple in construction and inexpensive to manufacture.

Other objects will hereinafter appear.

The invention is illustrated by way of example in the accompanying drawings, in which:—

25 Figure 1 is a perspective view illustrating the application of the present invention to a can.

30 Figure 2 is a perspective view of a card holder restricted in accordance with the invention and illustrating the manner in which it may be secured to a can or the like.

35 Figure 3 is a view similar to Figure 1, but showing a modified form of the present invention, and

40 Figure 4 is a rear elevation of a modified form of the card holder shown in Figure 3 and also showing in dotted lines the means for securing the same to a can or other container.

45 Referring to the drawings more particularly, the card holder illustrated in Figures 1 and 2 comprises a strip of sheet metal 10 preferably rectangular in cross section as shown and having formed upon its lower edge a pair of upwardly turned tangs 11, one at each end thereof and also having formed at the upper end of each side edge an inwardly bent tang 12. The inwardly bent portion of each of the tangs 11 and 12 are

50 sufficiently spaced from the adjacent side surface of the strip 10 so that a price card 13 may be slid therebetween and positioned as shown in Figure 1. The strip 10 is also provided with a pair of recesses 14, one being disposed adjacent each end of the strip and

thus forming an intermediate portion 15. Each edge of the intermediate portion 15 at the upper end thereof is provided with an extension 16 which is disposed at substantially right angles to the plate 10 and having its outer end terminating in a downwardly extending finger 17. Each finger 17 is twisted at its lower end to provide a portion 18 which will be disposed in substantially the same plane as the sides of the strip 10.

In positioning the price card holder upon a can 19 as shown in Figure 1 a rubber band 20 is preferably used although a string or other means may be used and the rubber band is placed between the upper portions of the fingers 17 and the intermediate portion 15 of the strip 10 and thus supporting the tag holder. The rubber band is of course placed about the can as shown in Figure 1 and then a price card 13 may be slipped in position.

Referring to Figures 3 and 4 the card holder in this instance comprises a narrow strip of sheet metal 21 having formed upon its each end an inwardly bent portion 22. A second strip 23 of substantially the same width is riveted as at 24 to the strip 21 at a point intermediate its ends and then the one end portion is bent to form an L-shaped portion 25, while the other end portion of the strip 23 is formed with a bent over portion 26. As is obvious the bent over portions 22 of the strip 21 and likewise the bent over portion of the strip 23 are adapted to 90 slidingly receive a price card 27, as shown in Figure 3 and support the same. In applying this card holder a rubber band 28 may be positioned upon a cam 29 as shown in Figure 3 and then the L-shaped portion 25 of the strip 23 hooked over the rubber band as likewise shown in Figure 3. It also may be again mentioned that the rubber band 28 is not indispensable. Ordinarily a string or other similar means can be used for the 95 same purpose if so desired.

I claim:

1. A card holder comprising in combination, a plate having formed upon its forward face suitable means for detachably supporting a card and having a recess formed adjacent each end thereof, a finger extending outwardly and downwardly from the inner edge of each recess, and a band extending beneath the fingers and over the plate portion 110

intermediate the recesses and adapted to secure the card holder to a container.

2. A card holder comprising in combination, a plate having formed upon its forward face suitable means for detachably supporting a card having a recess formed adjacent each end thereof, a finger extending downwardly from the upper edge of each recess and at a point intermediate the length of said upper edge, and said fingers each having their lower end portions disposed in a plane similar to that of the plate.

3. A card holder comprising in combination, a plate having formed upon its forward face suitable means for detachably supporting a card and having a recess formed adjacent each end thereof, a finger extending downwardly from the upper edge of each recess and at a point intermediate the length of said upper edge, and said fingers each being spaced to the rear face of the plate and having their sides disposed in a plane transversely to the plate.

CLAYTON EARL OSBURN.
